UNITED STATES PATENT OFFICE.

ARTHUR F. LEVITT, OF LOS ANGELES, CALIFORNIA.

BUILDING WALL.

Application filed September 8, 1925. Serial No. 54,994.

This invention relates to improvements in building walls.

An object of the invention is to provide an improved building wall construction which may be formed of self-hardening plastic material such as concrete and which will not require the use of wooden forms or the like.

The improved wall consists essentially of two parallel walls constituting the forms for the concrete. These walls are formed or built up of tiles or slabs and the self-hardening material is poured between them, so that when the material hardens the two parallel walls formed of the tiles form the exterior surfaces of the wall.

With the foregoing and other objects in view which will be made manifest in the following detailed description and specifically pointed out in the appended claims, reference is had to the accompanying drawings for an illustrative embodiment of the invention, wherein;

Figure 1 is a partial side elevation of the wall of the improved construction.

Fig. 2 is a top plan view of the wall, parts being broken away and shown in horizontal section.

Fig. 3 is a vertical section taken upon the line 3—3 of Fig. 1.

Fig. 4 is a vertical section taken upon the line 4—4 of Fig. 1.

Fig. 5 is a perspective view of one of the tiles used in forming the two parallel walls.

Fig. 6 is a top plan view of the tile.

Fig. 7 is a bottom plan view of the tile.

Fig. 8 is an end elevation of the tile shown in Fig. 5.

Fig. 9 is a perspective view illustrating a portion of one of the sheet metal connectors.

Referring to the accompanying drawings wherein similar reference characters designate similar parts throughout, the improved wall may be built upon any suitable foundation such as indicated at F. It consists of two parallel walls indicated at 10 and 11 respectively which walls are formed or built up of tiles T. The tiles are arranged in horizontal courses and have their vertical joints broken or staggered as clearly shown in Fig. 1. Preferably the tiles on both the inner and outer walls are directly opposite each other so that the vertical joints of corresponding courses forming the two walls will be upon the same transverse planes.

In the preferred form of construction the tiles have bead and groove joints between each other and as clearly shown in Figs. 5 to 8 inclusive, the top and one side edge of each of the tiles have beads 12 formed thereon and the opposite side edge and the bottom edge have grooves 13 formed thereon, so that when the tiles are assembled the beads fit within the grooves of adjacent tiles.

Sheet metal connectors which serve also as reinforcing members, such as 14 are arranged vertically between the courses and opposite alternate courses. These sheet metal connectors are provided with extensions 15 which are crimped as indicated at 16 complimentary to the beads and grooves formed on the tiles. The extensions 15 are arranged between the vertical joints between the tiles and in this manner the connectors keep the inner and outer walls in proper spaced relation while the self-hardening plastic material such as concrete C is poured between the walls. The sheet metal connectors preferably extend from top to bottom of the walls, although they may be formed of sections if found desirable. When the inner and outer walls are built up and the sheet metal connectors are in place the concrete C is poured between the walls imbedding the connectors therein. When the concrete hardens the walls are connected together by it and the tiles are connected to each other. These tiles remain in place and form the outer surfaces of the wall so constructed. If desired the tiles may be tinted or be ornamented in any desired manner.

From the above described construction it will be readily appreciated that it is unnecessary to construct the conventional wooden forms in forming the wall and the blocks or tiles can be formed at some central molding plant and shipped to the job where they can be easily and quickly set up with the connectors, and the concrete then poured.

Not only does the improved construction eliminate the use of forms but it also provides for an ornamental finished appearance upon the wall if desired.

If at any time it is wished to form a hollow wall construction it will be readily appreciated that suitable cores can be arranged between the inner and outer walls and between the sheet metal connectors. When the concrete is poured it is poured

2
about such cores forming the hollow spaces in the wall. When such cores are used however, they are spaced from the interior surfaces of the inner and outer walls 10 and 11.

5. Various changes may be made in the details of construction without departing from the spirit or scope of the invention as defined by the appended claims.

What I claim is:

- 10 1. A building wall comprising two walls built up of horizontal courses of tiles, having vertical joints broken or staggered, said tiles having bead and groove vertical joints, sheet metal connectors positioned between the walls in vertical position, having crimped extensions positioned between the vertical joints of the tiles of alternate
- 15

courses, and a self-hardening plastic material disposed between the two walls imbedding the connectors therein.

20

2. A building wall comprising two walls built up of horizontal courses of tiles having vertical joints broken or staggered, sheet metal connectors positioned between the walls which are more than two courses high, said connectors having extensions between the joints of the tiles of alternate courses, and a self-hardening plastic material disposed between the two walls, imbedding the connectors therein.
